[57] CLAIM

The ornamental design for a water catcher for an appliance, as shown and described.

DESCRIPTION

FIG. 1 is a perspective view taken from the top, front and right side of a water catcher for an appliance showing my new design;

FIG. 2 is a top plan view thereof;

FIG. 3 is a front elevational view thereof, the rear being the same as the front;

FIG. 4 is a bottom view thereof; and,

FIG. 5 is right side elevational view thereof, the left side being the same as the right side.

The fragmentary broken line showing of a drain pipe in FIG. 3 is for purposes of illustration only and forms no part of the claimed design.
